(57) **CLAIM**

The ornamental design for a gusset pouch, as shown and described.

DESCRIPTION

FIG. 1 is a perspective view of the gusset pouch showing the design;

FIG. 2 is a front view thereof;

FIG. 3 is a side view thereof;

FIG. 4 is a top view thereof; and,

FIG. 5 is a bottom view thereof.

The portions of the disclosure shown in broken lines form no part of the claimed design.

1 Claim, 4 Drawing Sheets(56)
